UNITED STATES PATENT OFFICE.

WILLIAM A. MILLER, OF ST. LOUIS, MISSOURI.

GUARD FOR POCKET-BOOKS.

1,254,426.

Specification of Letters Patent. Patented Jan. 22, 1918.

Application filed December 1, 1916. Serial No. 134,274.

To all whom it may concern:

Be it known that I, WILLIAM A. MILLER, citizen of the United States, residing in the city of St. Louis and State of Missouri, have 5 invented new and useful Improvements in Guards for Pocket-Books, of which the following is a specification.

This invention relates to a device which is an attachment for a pocket book or bill 10 fold, and which operates as a guard to prevent one's pocket book from being taken from the pocket by a pickpocket. The guard also operates as a safety device to prevent the pocket book from being thrown accidentally from one's pocket.

The general object of the invention is to provide a very simple device for this purpose, which is very inexpensive in its construction, and constructed in such a way that 20 it will engage the pocket and cannot be released except by thrusting one's hand deeply into the pocket, that is to say, by such a movement as would certainly be felt by a person whose pocket was being robbed.

25 Further objects of the invention will appear hereinafter.

In the drawing, which illustrates the preferred embodiment of my invention,

Figure 1 is an elevation showing the rear 30 portion of a pair of trousers having a hip pocket and illustrating the relation of the device to the pocket carrying it,

Fig. 2 is a vertical section through the pocket shown in Fig. 1 indicating the pocket 35 book carried therein, and illustrating the manner in which the guard operates normally to prevent the removal of the pocket book,

Fig. 3 is a vertical section showing a portion of the wall of the pocket book, and 40 showing the guard in longitudinal section, and

Fig. 4 is a plan of the guard removed from the pocket book.

45 Though the pocket book and guard may be carried in any kind of pocket, for the purpose of illustration, I have represented it in the accompanying drawing as carried in a hip pocket.

50 In the drawing 1 represents the hip portion of the trousers in which is formed a hip pocket 2, the mouth 3 of the pocket being located at its upper end in the usual manner. A pocket book or bill fold 4 of any common 55 form is represented as carried in the pocket 2.

In applying my invention to such a pocket book I provide a guard 5 which comprises a member 6 held on the flat side face 7 of the pocket book, preferably near the upper 60 end of the pocket book. And this member 6 extends laterally with respect to the plane in which the pocket book lies, its outer end engaging the inner face of the outer wall 8 of the pocket 2, and operating to hold this 65 wall distended. The member 6 is preferably in the form of a plunger comprising a light metal cylindrical casing 9, in which is set a plug 10 preferably of a yielding material such as soft rubber. This plunger is mov- 70 ably mounted in a tubular guide 11 attached in any suitable manner to the pocket book. If it is to be permanently attached I provide a circular plate or disk 12 rigidly 75 carrying the guide. The plunger 6 is held in place, and its movement in and out is limited by means of a cross pin 13 passing through the casing 9 and through a slot 14 formed in the plunger 10.

I provide means for forcing the member 80 6 outwardly to cause the end face of the plunger to exert substantial pressure against the inner face of the outer wall of the pocket. For this purpose I prefer to provide a helical spring 15 within the tubular 85 guide behind the plunger 6, and I prefer to form the projecting tip 16 of the plunger with a transverse inclined end face 17, so that when the device is attached in place the longest portion of the plunger is disposed 90 toward the mouth 3 of the pocket. This gives the upper portion of the plunger the effect of a rudimentary tooth or spur which presses against the cloth (see Fig. 2) and tends to increase the force which would be 95 necessary to pull the pocket book out of the pocket.

In order to facilitate the attachment of the guard to the pocket book, I prefer to provide the plate 12 with a plurality of 100 small rivet holes 18, to receive rivets 18^a and in order to give the device a neat appearance I prefer to cover the outer face of the plate 12 with a leather disk 19 which, if desired, may match the material out of 105 which the pocket-book is made. And beyond the edge of the plate 12 I prefer to provide an annular piece or ring 20 of leather which brings out the middle layer of material to the outer edge of the cover 110 disk 19, as shown in Fig. 3. In this way the edge of the metal is covered and the

leather pieces may be conveniently sewed to the pocket book.

- When the pocket book is in the pocket the tip of the guard engages the outer side 5 of the pocket, substantially as indicated in Fig. 2. According to my invention the device is devoid of any means of moving the plunger inwardly to disengage it from the outer face of the pocket. Hence, it is evident that if a pickpocket takes hold of the upper edge of the pocket book and attempts to pull it up through the mouth of the pocket the guard would prevent such a movement.
- 15 When the person carrying the pocket book wishes to remove it from his pocket he simply thrusts his hand down into the interior of the pocket on the outer side of the pocket book. This presses the outer 20 wall of the pocket outwardly, and the thickness of the hand is sufficient to disengage the outer wall of the pocket from the end of the plunger, whereupon the pocket book can be readily withdrawn. In thrusting the 25 hand into the pocket in the manner suggested the movement will be facilitated if the tubular guide 11 is permitted to pass into the space between two of the fingers of the hand. At the same time the device will 30 not offer any obstruction to the inward movement of the hand.

If a man carrying the pocket book and guard in his hip pocket should stoop forward, evidently the spring and the rubber 35 will give under the increased pressure and thus relieve the strain on the pocket at the guard.

It is understood that the embodiment of the invention set forth herein is only one 40 of the many embodiments the invention may take, and I do not wish to be limited in the practice of the invention, nor in my claims, to the particular embodiment set forth.

I claim:

- 45 1. A guard for preventing accidental removal of a pocketbook from one's pocket,

consisting of a member projecting laterally from the side face of the pocket book to engage the inner face of the outer wall of the pocket and hold said outer wall in a distended position, whereby the pressure of the said wall of the pocket against said member operates to prevent accidental displacement of said pocketbook, and means for yieldingly forcing said member outwardly. 55

2. A guard for preventing accidental removal of a pocketbook from one's pocket, consisting of a guide projecting laterally from the side face of the pocketbook, and a plunger movably mounted in said guide, 60 projecting from said guide and having an end face to engage the inner face of the outer wall of the pocket and hold the same in a distended position, and means tending to move said plunger outwardly in said 65 guide.

3. A guard mounted on the side face of a pocket book, and consisting of a tubular guide extending laterally with respect to the plane in which the pocket book lies, a 70 member movably mounted in said guide and normally projecting therefrom to press against the inner face of the outer wall of the pocket in which the pocket book is carried and thereby hold the pocket book 75 against accidental removal, and a spring within said tubular guide for normally forcing said member outwardly.

4. A guard for preventing accidental removal of a pocketbook from one's pocket, 80 consisting of a tubular guide projecting laterally from the side of the pocketbook, a plunger movable in said guide and having a tip of yielding material for engaging the inner face of the outer wall of the pocket, 85 and a spring within said guide for normally forcing said plunger outwardly to press the same against said outer wall and thereby hold the same distended.

In testimony whereof, I have hereunto 90 set my hand.

WILLIAM A. MILLER.
